UNITED STATES PATENT OFFICE.

LINCOLN GOODE, OF PITTSBURG, CALIFORNIA.

LUMBER-CURING KILN.

1,266,791.

Specification of Letters Patent. Patented May 21, 1918.

Application filed July 30, 1917. Serial No. 183,466.

To all whom it may concern:

Be it known that I, LINCOLN GOODE, citizen of the United States, residing at Pittsburg, in the county of Contra Costa, State of California, have invented a new and useful Lumber-Curing Kiln, of which the following is a specification in such full and clear terms as will enable those skilled in the art to construct and use the same.

10 This invention relates to a lumber curing kiln, and its object is to provide means for the circulation of air in the kiln during the time the lumber is being cured without an undue loss of heat.

15 Another object of the invention is to provide means for humidifying the kiln to maintain the necessary moisture content in the air to prevent injury to the lumber.

20 It will be understood by those skilled in the art that in curing lumber, it is necessary to maintain the lumber in an atmosphere of the proper temperature and of the proper moisture content to prevent its injury for such a time as is necessary to thoroughly 25 dry it, and the moisture contained in the air must be varied from time to time according to the condition of the lumber.

In other words, in a very short time the 30 outer fibers of the lumber will become as dry as they should be finally, while the inner fibers contain an excess of moisture. During this period, the air passing over the lumber must be moistened to prevent it from 35 injuring the lumber by too rapid outside drying.

Later on, as the inner fibers become thoroughly cured, it is necessary to use air as dry as possible, in order to completely remove all of the moisture from the lumber, 40 but this is not the case until near the time for the curing process to end.

Other objects of the invention will appear as the description proceeds.

An embodiment of the invention is shown 45 in the drawings in which the same reference numeral is applied to the same portion throughout, but I am aware that there may be modifications thereof.

Figure 1 is an end elevation of the kiln 50 with the doors open and with the casing of the lower portion of the kiln removed for the purposes of illustration,

Fig. 2 is a plan view in section below the floor upon which the steam pipes and 55 car tracks are laid,

Fig. 3 is a vertical section of a portion of the kiln adjacent the circulating fan, and

Fig. 4 is a plan view of a portion of the kiln showing the arrangement of the tracks and piping therein.

60

The kiln is installed within a building having vertical walls 1, 2 and 3, covered with a roof 4 and strengthened with cross pieces 5, a vertical post 6 at one end of the building serves to assist in holding the gable 65 end, and said post rests upon a cross beam 7, said cross beam being supported by means of the posts 8 to 11 inclusive. The space between the walls and posts 8 to 11 inclusive is ordinarily filled by means of removable 70 doors 12 to 16 inclusive, which have been removed from Fig. 1 for purposes of illustration.

It will be understood by those skilled in the art that, for the convenience of the kiln 75 operator, the rails 17 to 20 inclusive, upon which the car loads of lumber are placed, are installed upon suitable stringers 21 to 24 mounted upon a series of posts 25, which are all of a convenient height to permit the 80 operator to walk below the cross stringers 7 when attending to the air conditions within the kiln. Boards 26 are provided at the 85 sides of the track for the convenience of the operator in examining the lumber on the cars, but the remaining space is covered with long strings of steam pipes 27, 28 and 29, receiving steam from the risers 30, 31, 32 respectively, and which are connected with a main steam pipe 33, the latter having 90 a water trap 34 connected therewith. At the opposite end of the building the steam pipes are connected with one transverse pipe 35, which is in turn connected with a water trap 36 outside the building. Extending 95 from end to end of the building, below the level of the tracks is a ventilating box 37. This box has a plurality of ventilator slides 38, which may be opened or closed to increase or diminish the supply of fresh air 100 coming into the kiln; and in the walls of the kiln there are a plurality of flues 39, said flues having chimneys 40 extending above them to allow the escape of air from the kiln. Extending through the middle of 105 the kiln is a large air pipe 42 which has a plurality of slides 43 opening and closing openings in said air pipe, as may be required by the condition of the lumber being treated. This air pipe receives its air from 110

the fan 44 which in turn draws air from the air pipe 45 having two branches 46, 47. The branch pipes 46, 47 likewise have regulators 48 to determine the quantity of air 5 they will receive. A steam pipe 49 extends down the center of the coil adjacent the pipe 42, and it has two spray devices 50, 51 connected therewith for the purpose of discharging steam into the kiln when the humidity of the air falls too low.

It will of course be understood by those skilled in the art that these steam pipes have such valves as may be required to operate them at whatever points may be necessary. 15 The front of the kiln is closed when the lumber is in place by means of suitable doors 52.

It will also be understood by those skilled in the art that any suitable platform outside the kiln is used to enable the car loads of lumber to be run up to the level of the tracks 19 and 20, within the kiln, such platform forming no part of the present invention, however, and not being illustrated 25 here.

The operation of the kiln is as follows:— Assuming several car loads of lumber to have been placed therein, the doors 52 are closed and the steam pipes 27 to 29 are 30 heated to such a temperature as may be desirable to cure the lumber. The fan 44 is then started, and as the air therefrom is blown through the pipe 42 and delivered to the various parts of the kiln it passes 35 up toward the roof and then down and into the branch pipes 46, 47, and back to the fan, the process being repeated indefinitely, and the air in the kiln being in this way made substantially uniform throughout the same.

If the air as determined by an inspection 40 of the lumber is too dry and is absorbing moisture therefrom so as to be liable to collapse the grain of the lumber, the attendant may pass some steam through the pipes 50, 45 51 into the kiln and thereby bring up the humidity to a high enough point to prevent the rapid curing of the lumber.

It will be understood by those skilled in the art that, while a comparatively small kiln has been illustrated in the drawings, 50 ordinarily lumber kilns of this character are of a length of several hundred feet, and may have doors to permit the ingress and egress of the lumber cars at both ends if desired. 55

It is also to be observed that, in as much as the openings into the flues 39 are near the floor of the kiln, practically a very small quantity of the hot air of the kiln is lost by the ventilation while it is being continually 60 stirred up and shifted from one place to another in the building by means of the fan.

Having thus described my invention, what I claim as new and desire to secure by Letters Patent of the United States is as 65 follows, express reservation being made of permissible modifications.

1. A lumber kiln comprising a building having inlet and outlet ventilating openings near the lower portion thereof, car tracks 70 extending into the building and adapted to receive the cars with piles of lumber thereon, a fan, having pipes for circulating the air in said building, means to regulate the flow of air from said pipes as may be required at different points in the building, 75 and spray pipes for increasing the humidity of the air in the building.

2. A lumber kiln comprising a building having flues in the walls thereof, with ventilating openings below the supports for the lumber, and inlet ventilating trunk extending into the building and having a plurality of openings, a fan having inlet and discharge pipes extending into the building, 80 each pipe having a plurality of openings, slides to control the fan pipe openings to circulate the air in different parts of the kiln, and spray pipes to alter the humidity 85 of the air in the kiln. 90

In testimony whereof I have hereunto set my hand this 24th day of July, A. D. 1917.

LINCOLN GOODE.
